UNITED STATES PATENT OFFICE.

JOHN R. LOMAS, OF NEW HAVEN, CONNECTICUT, ASSIGNOR TO BERNARD SHONINGER, OF SAME PLACE.

DESIGN FOR A REED-ORGAN CASE.

Specification forming part of Design No. **6,603**, dated April 22, 1873; application filed March 15, 1873.

To all whom it may concern:

Be it known that I, JOHN R. LOMAS, of the city and county of New Haven and State of Connecticut, have invented a Design for an Organ-Case, of which the following is a specification:

My improved design for an organ-case is fully represented in the accompanying photographic illustration, to which reference is made.

First, I make book-cases, F, with bevel corners, A, extending to the front of the keys. Second, I provide the panel B for the book-rack with moldings E. Third, I make lamp-stands in the form of a vase, as shown at G. Fourth, I construct the book-case F with doors,

ornamented as shown, thus producing a very happy effect and an attractive appearance.

What I claim is—

1. The design for the bevel ends A of the case extending to the front of the keys, as described and shown.
2. The moldings E on the panel B, substantially as shown.
3. The vase-shaped lamp-stands G, substantially as described and shown.
4. The doors of book-cases F, ornamented as shown and described.

Witnesses: JOHN R. LOMAS.
